UNITED STATES PATENT OFFICE.

CHARLES F. ALLEN, OF COLUMBUS, OHIO.

DESIGN FOR A GAS OR VAPOR BURNER.

SPECIFICATION forming part of Design No. 26,035, dated September 15, 1896.

Application filed July 29, 1896. Serial No. 600,986. Term of patent 7 years.

To all whom it may concern:

Be it known that I, CHARLES F. ALLEN, a citizen of the United States, residing at Columbus, in the county of Franklin and State 5 of Ohio, have invented and produced a certain new and original Design for a Gas or Vapor Burner; and I do declare the following to be a full, clear, and exact description of the invention, such as will enable others skilled in 10 the art to which it appertains to make and use the same.

Figure 1 is a perspective view of a natural-gas burner, showing my design; and Fig. 2 is 15 a longitudinal section of the same.

The essential feature of my design consists

in the convex-walled outer annular ring A, the inner annular flaring wall B, having a beveled edge C overlapping the inwardly-converging annular edge D, and an integral conical spindle E, projecting through a horizontal 20 circular orifice F in the outer convex wall A.

What I claim is--

A design for a gas or vapor burner, substantially as herein shown and described.

In testimony whereof I hereunto affix my 25 signature in presence of two witnesses.

CHARLES F. ALLEN.
